UNITED STATES PATENT OFFICE.

HOMER A. BENEDICT, OF SYRACUSE, NEW YORK.

SWITCH CONSTRUCTION.

1,086,639.

Specification of Letters Patent. Patented Feb. 10, 1914.

Application filed November 22, 1912. Serial No. 732,844.

To all whom it may concern:

Be it known that I, HOMER A. BENEDICT, of Syracuse, in the county of Onondaga and State of New York, have invented a certain new and useful Switch Construction, of which the following is a specification.

This invention has for its object the production of a particularly simple and efficient switch construction especially applicable for effecting the dimming of incandescent electric lamps; and it consists in the novel features hereinafter set forth and claimed.

In describing this invention reference is had to the accompanying drawings in which like characters designate corresponding parts in all the views.

Figure 1 is a plan view of one form of switch construction, partly in section. Fig. 2 is a sectional view partly in elevation. Fig. 3 is a plan of the base of the resistance means. Figs. 4 and 5 are plan views of the switch arms of a three circuit rotary snap switch embodied in my switch construction. Figs. 6 and 7 are diagrammatic views of said three circuit rotary snap switch. Figs. 8, 9 and 10 are diagrammatic views illustrating respectively the electrical connection when all the resistances are cut in, the connection when one of the resistances is cut out, and the connection when all the resistances are cut out.

This switch construction comprises, generally, resistance coils, switch terminals, two of which are connected to the lead wires, one of said two terminals being connected to one of the resistances and the other terminals being connected to the resistances, and switch arms operable to engage the terminals to cut out the resistances or cut in the same, or to break the circuit through the switch. As here shown the resistances are arranged in concentrically arranged coils arranged coaxially with the axis of the switch.

1 is a cupped base of insulation.

2, 3 and 4 are rings of insulation located concentrically within the base and having resistance coils 5, 6 and 7 thereon, the bottom of the base 1 being formed with grooves 50 or seats 8 for the rings and also with openings 9 for the lead wires 10 which are connected to the terminals of the switch. The coils 6 and 7 are connected together to act as one resistance unit.

11 is the base of a rotary snap switch, the snap switch here shown being a three circuit

single pole switch, two of the terminals 12, 13 thereof being connected to the line wires 10 respectively, and the third terminal 14 being connected to one of the terminals as 12 60 through one of the resistances as 5, and the third and fourth terminals 14 and 15 being connected through the resistance coils 6, 7. The arms 16 and 17 of this three pole switch are arranged normally to be in an off position and upon the first turn of the button 18 of the switch, the contacts of the arms 16, 17 are arranged to make a connection shown in Fig. 8 in which both resistances 5 and 6 and 7 are in the circuit in series between the 70 terminals 12 and 13. Upon the next turn of the button 18, the contacts of said arms 16, 17 operate to engage the terminal 14 and the terminal 13 so that but one resistance 5 is in the circuit as shown in Fig. 9 the resistances 6 and 7 being short circuited. Upon the next turn of the button 18 although a plurality of contacts of the switch arms 16, 17 are engaged with different terminals, two of such contacts engage with the terminals 80 12 and 13 so that the resistance coils 5, 6 and 7 are cut out of the circuit as shown in Fig. 10 and a current of maximum strength flows through the switch so that the lamp connected in circuit will give maximum 85 light.

The three circuit snap switch is of any desirable form, size and construction and any commercial form may be used and hence as these three circuit switches are well known, 90 it is thought that further description herein is unnecessary.

This invention is particularly advantageous in that it provides means of attaching the resistances by which an incandescent 95 electric lamp can be dimmed, which means can be connected to commercial switches.

What I claim is:

1. The combination of a cupped base, a resistance coil mounted in the base, and a 100 switch including a base mounted on the first-mentioned base and having terminals thereon connected to the resistance coil, substantially as and for the purpose set forth.

2. The combination of a cupped base, a 105 plurality of concentrically arranged rings located within the base, resistance coils encircling said rings, a rotary switch having its base inserted into the first-mentioned base above said rings, terminals of the 110 switch being connected to the resistance coils whereby in different closed positions of the

switch, different resistances are connected in circuit, substantially as and for the purpose described.

3. The combination of a cupped base, a plurality of concentrically arranged rings in the base detachable therefrom, the base also having openings for line wires, the openings communicating with the interior of the base between two of the rings, with a three circuit single pole snap switch having its base mounted in the first-mentioned base, two of the terminals of the switch being designed to be connected to the lead wires and one of the resistance coils being connected to one

of said two terminals and to the third terminal, and another of said coils being connected to the third terminal and the fourth terminal, substantially as and for the purpose specified. 15

In testimony whereof, I have hereunto signed my name in the presence of two attesting witnesses, at Syracuse, in the county of Onondaga, in the State of New York, this 7 day of Oct. 1912.

HOMER A. BENEDICT.
